UNITED STATES PATENT OFFICE.

GEORGE A. CURTIS, OF MEDFORD, MASSACHUSETTS.

SHOE-NAIL.

1,033,159.

Specification of Letters Patent. Patented July 23, 1912.

Application filed November 14, 1911. Serial No. 660,238.

To all whom it may concern:

Be it known that I, GEORGE A. CURTIS, a citizen of the United States, and a resident of Medford, in the county of Middlesex and State of Massachusetts, have invented certain new and useful Improvements in Shoe-Nails, of which the following is a specification.

The object of this invention is to provide a shoe nail having an improved form of tapering portion having a less tendency to cripple while driving than the ordinary nail now in use, and which portion is longer, relatively to the length of the shank portion, than usual, resulting in advantages herein-after described.

A further object is the provision of such a nail having a formation that will present no angle along the inner curve of the 20 clenched end to bear on the surface of the work held by such clenched end.

To these ends the invention consists in the nail substantially as hereinafter described and claimed.

25 Of the accompanying drawings,—Figures 1 and 2 are side elevations of two of my improved nails, one being straight and the other showing the result of the clenching operation. Fig. 3 represents a section on line 3—3 of Fig. 1. Fig. 4 represents a section on line 4—4 of Fig. 1. Fig. 5 represents a section on line 5—5 of Fig. 1.

Similar reference characters indicate the same or similar parts in all of the views.

35 The round and transversely notched shank *a* and head *b* may be, as indicated, according to a well known form of shoe nail; but the tapering portion is longer, relatively to the length of the shank, than usual, this greater 40 length being possible due to the novel form of said tapering portion as presently described. Said tapering portion is formed with four flat sides *c*, *c*, *c*, *c*, which meet each other at a right angle, said flat sides being 45 exactly alike and equal to each other and straight from where they join the round shank portion at *d* to a slightly rounded tip *e*, so that a transverse section on either of the lines 3, 4 or 5 of Fig. 1, or between those 50 lines, will be square as illustrated in Figs. 3, 4 and 5. It will now be understood that if the tapering portion were somewhat flattened to oval or rhomboidal form, and still made as long as shown in Fig. 1, the stock

would be so thin at intermediate points, especially from line 4 to line 5, that the nail would be liable to "cripple" when being driven; in other words, to bend and go crooked before getting through the work. But owing to my improved structure of 60 square cross section from end to end of the taper, the said taper can extend unusually far up from the tip and still leave sufficient thickness of stock to insure straight driving, as seen by reference to Figs. 4 and 5. This 65 increased length of taper increases the length of the portion of the nail which is capable of being curled up by the usual clenching operation, and therefore there need be less careful selection of length of 70 nails to suit particular thicknesses of work. In other words, one length of nail can be used for a greater variety of thicknesses of work. Another advantage is that when the nail is clenched, it practically invariably 75 curls in a plane parallel with two parallel flat sides. In other words, it curls, as shown in Fig. 2, with one flat side *c* forming the inside of the curl. This is because the greater thickness on a line intersecting the 80 center and two angles resists curling in such direction as to bring an angle inside the curl. Therefore, although the nail may curl in either one of four directions, it will be practically certain to so curl that a flat side 85 will bear on the surface of the work through which the nail is driven and against which surface the inside of the curl bears, and consequently the inside of the curl will present 90 no angular rib to cut into the work. 90

I claim:—

A shoe nail having a tapered portion square in cross section and presenting four flat sides which converge toward the tip, said tip being rounded, all four corners or 95 angles between said flat sides also converging toward the tip, whereby said tapered portion will possess the same square cross sectional shape at different distances from the tip but gradually of less cross sectional 100 area toward the tip.

In testimony whereof I have affixed my signature, in presence of two witnesses.

GEORGE A. CURTIS.
